UNITED STATES PATENT OFFICE.

ROSS RUE, OF ALLIANCE, OHIO.

DITCHING-JACK. BEST AVAILABLE COP

SPECIFICATION forming part of Letters Patent No. 784,890, dated March 14, 1905.

Application filed January 12, 1905. Serial No. 240,840.

To all whom it may concern:

Be it known that I, ROSS RUE, a citizen of the United States, residing at Alliance, in the county of Stark and State of Ohio, have invented certain new and useful Improvements in Ditching-Jacks; and I do hereby declare that the following is a full, clear, and exact description of the same, reference being had to the annexed drawings, making a part of this specification, and to the numerals of reference marked thereon, in which:

Figure 1 is a longitudinal section of the jack and longitudinal section of the handle, showing handle folded in dotted lines. Fig. 2 is a section on line 2-2, Fig. 1. Fig. 3 is a view of the jack socket head and foot, showing the cap removed. Fig. 4 is a detached perspective view of the cap. Fig. 5 is a face view of the foot.

20 The present invention has relation to ditching-jacks; and it consists in the novel construction hereinafter described, and particularly pointed out in the claims.

Similar numerals of reference indicate corresponding parts in all the figures of the drawings.

In the accompanying drawings, 1 represents the jack-stem, which may be formed of any desired length and is provided with an enlarged 30 screw-threaded portion 2, upon which screw-threaded portion is adjustably attached the jack socket stem or member 3. The jack-stem 1 is provided with the foot 4, which foot is securely attached to the jack-stem by means of the rivet 35 5 or its equivalent. To the jack socket stem or member 3 is formed integral therewith the head 6, which head is for the purpose of entering the socket 7, formed in the foot 8.

The socket stem or member 3 is provided 40 with the flange 9, which flange is provided with the groove 10 and the cross-slots 11. Around the flange 9 is located the yoke 12, to which yoke is attached the flanged stem 13 and the flanged stem securely clamped upon 45 the flange 9 by suitable nuts 14, by which arrangement the stem 13 is held in fixed relation with the socket-stem 3. Within the stem 13 is located the reciprocating bar 15, which bar is provided with the shank 16 and around 50 which shank is located the spring 17, which

spring is for the purpose of normally holding the reciprocating bar 15 in engagement with the cross-slots 11. To the outer end of the stem 13 are pivotally attached the handle members 18, which handle members are preferably formed integral with the handle proper 19. Between the handle members 18 and the handle 19 is located the link-like portion 20, which link-like portion receives the outer end of the pull-bar 21, which pull-bar is provided with the eye or ring 22. The pull-bar 21 is pivotally attached to the shank 16. It will be understood that when the handle 19 is moved around a center forming the longitudinal axis of the jack-shank 1 and the socket member 3 65 said socket member will be rotated when the reciprocating bar 15 is engaged with one of the cross-slots 11, and thereby rotate the socket member 3 upon the screw-threads of the shank 1, and when the socket member 3 70 is rotated in one direction it will move the feet 4 and 8 away from each other or, in other words, will expand the length of the jack, and when the handle 19 is rotated in the opposite direction it will shorten the length of the jack 75 by moving the feet toward each other.

It is well understood that in ditching-jacks it is difficult to give the handle a full revolution; but to overcome this difficulty the reciprocating bar 15 is provided and operated by 80 the hand by means of the eye or ring 22. The handle after it has been moved as far as convenient is released from operative contact with the socket member 3 by disengaging the reciprocating bar from one of the cross-slots, 85 after which the handle 9 can be given a backward movement and the bar 15 engaged in a different cross-slot, after which a forward or operative movement can be given to the handle.

For the purpose of moving the handle out of the way after the jack proper has been adjusted to hold the planks or other structure of the ditch it is turned upon the pivotal points of the handle members 18, and in order that a 95 pivotal connection may be made between the pull-bar 21 and the shank 16 said shank and pull-bar are pivotally connected together at a point near and a little to one side of the pivotal point of the handle proper, by which ar- 100

arrangement the handle can be moved out of the way without disconnecting any of the operative parts.

For the purpose of providing proper contact for the heads 4 and 8 said heads are provided with contact-teeth 23, and for the purpose of forming a light structure and at the same time bringing a portion of the contact-teeth 23 some distance away from the axis of the jack shank and socket members 3 the contact ends of the heads 4 and 8 may be of the form of an ellipse, by which arrangement some of the contact-teeth are located a sufficient distance away from the axis to better prevent any slipping of the heads.

For the purpose of holding the head 6 in the socket 7 the cap 24 is provided, which cap is held by suitable clamping-bolts. The spring 17 should of course be confined at its ends by means of a shoulder 24 and the bar 15. However, this is simply mechanical and needs no detailed description.

The stem 13 is provided with the spaced flanges 13*, which spaced flanges are located upon opposite sides of the flange 9, by which arrangement the stem 13 is held against lateral displacement.

Having fully described my invention, what I claim as new, and desire to secure by Letters Patent, is—

1. In a ditching-jack, the combination of

jack members adjustably connected together, said members provided with feet, and one of said members provided with a flange having an annular groove, cross-slots intersecting the groove, a yoke located around the flange, a stem connected to the yoke and located upon the grooved flange, said stem provided with a reciprocating bar adapted to engage the slots of the flange, a spring to actuate the reciprocating blade in one direction, a pull-bar and a handle pivotally attached to the shank, substantially as and for the purpose specified: 35

2. In a ditching-jack, the combination of jack members provided with screw-threads, 45 heads secured to the members, one of the members provided with a notched and grooved flange, a shank connected to the notched and grooved flange, a reciprocating bar adapted to engage the notches of the flange, a handle pivotally attached to the shank, and means for disengaging the reciprocating blade from the notched flange, substantially as and for the purpose specified.

In testimony that I claim the above I have 55 hereunto subscribed my name in the presence of two witnesses.
